(57) **CLAIM**

The ornamental design for the interactive intelligent panel, as shown and described.

DESCRIPTION

FIG. 1 is a front elevation view of the interactive intelligent panel with the drawer being located in the center;

FIG. 2 is a back elevation view of the interactive intelligent panel shown in FIG. 1;

FIG. 3 is a left side elevation view of the interactive intelligent panel shown in FIG. 1;

FIG. 4 is a right side elevation view of the interactive intelligent panel shown in FIG. 1;

FIG. 5 is a top plan view of the interactive intelligent panel shown in FIG. 1;

FIG. 6 is a bottom plan view of the interactive intelligent panel shown in FIG. 1;

FIG. 7 is a front perspective view of the interactive intelligent panel shown in FIG. 1;

FIG. 8 is a back perspective view of the interactive intelligent panel shown in FIG. 1;

FIG. 9 is a front perspective view of the interactive intelligent panel with the center drawer open;

FIG. 10 is a front elevation view of the interactive intelligent panel showing a second embodiment with the drawer being located on the left;

FIG. 11 is a back elevation view of the interactive intelligent panel shown in FIG. 10;

FIG. 12 is a left side elevation view of the interactive intelligent panel shown in FIG. 10;

FIG. 13 is a right side elevation view of the interactive intelligent panel shown in FIG. 10;

FIG. 14 is a top plan view of the interactive intelligent panel shown in FIG. 10;

FIG. 15 is a bottom plan view of the interactive intelligent panel shown in FIG. 10;

FIG. 16 is a front perspective view of the interactive intelligent panel shown in FIG. 10;

FIG. 17 is a back perspective view of the interactive intelligent panel shown in FIG. 10;

FIG. 18 is a front perspective view of the interactive intelligent panel shown in FIG. 10 with the left drawer open;

FIG. 19 is a front elevation view of the interactive intelligent panel showing a third embodiment with the drawer being located on the right;

FIG. 20 is a back elevation view of the interactive intelligent panel shown in FIG. 19;

FIG. 21 is a left side elevation view of the interactive intelligent panel shown in FIG. 19;

FIG. 22 is a right side elevation view of the interactive intelligent panel shown in FIG. 19;

(Continued)

FIG. 23 is a top plan view of the interactive intelligent panel shown in FIG. 19;
FIG. 24 is a bottom plan view of the interactive intelligent panel shown in FIG. 19;
FIG. 25 is a front perspective view of the interactive intelligent panel shown in FIG. 19;
FIG. 26 is a back perspective view of the interactive intelligent panel shown in FIG. 19; and,
FIG. 27 is a front perspective view of the interactive intelligent panel shown in FIG. 19 with the right drawer open.
The portions of the panel shown in broken lines form no part of the claimed design.
